UNITED STATES PATENT OFFICE

GEORGE E. STEUDEL, OF CHICAGO, ILLINOIS

CHECKERWORK

Application filed September 28, 1929. Serial No. 394,666.

My invention relates to blast furnace stoves and more especially to a checkerwork or brick construction used in the construction of the same.

It is essential in blast furnace operation that the air used for such a blast furnace be pre-heated before being drawn into the blast furnace, and as an accessory to each blast furnace a number of pre-heaters are required. These pre-heaters, or stoves as they are called, consist principally of a tall cell-like structure ordinarily of brick, so arranged that a number of passages are provided between the bricks from the bottom to the top of the stoves, and around the brick work is a steel shell. For the entrance of cold air into the bottom of the checkerwork, a number of passageways are provided over which an arch construction is necessary, and above the arches the main checkerwork is built. A common weakness and source of difficulty found in the ordinary type of stove construction is that the lower courses of brick work just above the arches have a tendency to break or crumble due to the improper distribution of superimposed weight upon them, and it is to overcome this difficulty that my present invention has been perfected. My invention is concerned especially with the several courses of bricks just above the arches in a blast furnace stove.

It is an object of my invention to provide an improved type of checkerwork construction. It is another object of my invention to provide a checkerwork construction in which the weight of the superimposed brickwork is transmitted uniformly to the sustaining arches. It is a further object of my invention to provide a checkerwork which reduces to a minimum the likelihood of crushing the lower courses.

Other objects and advantages will be brought out and become more apparent from the following specification, making reference to the accompanying drawings, in which—

Figure 1 is a condensed cross sectional elevation of a blast furnace stove embodying my invention;

Figure 2 is an abbreviated cross section

similar to Figure 1, but taken at right angles thereto;

Figure 3 is a plan view of the first course above the arches taken along the line 3—3 of Figure 2;

Figure 4 is a similar view taken along the line 4—4 of Figure 2, and shows the second course above the arches;

Figures 5 and 6 are views similar to Figure 4 taken along the lines 5—5 and 6—6 of Figure 2, respectively;

Figure 7 is a perspective view showing the four courses immediately above the arches, with part of the bricks removed;

Figure 8 is a perspective view of one of the special bricks used in my construction; and

Figure 9 is a similar view of a second special type of brick recessed intermediate its ends whereby to form when interlocked with another brick of the same construction a Greek cross.

Referring more particularly to the drawings, I show a blast furnace stove preferably circular in cross section, having a side wall 10 of steel or the like, within which is a brick side wall 11 of ordinary construction and a checkerwork 12 supported on foundation bricks 13 and arches 14 and 15. An interior wall 16 is provided, which meets the wall 11 as at 17 and forms a passageway 18 running the height of the stove, and communicating with the passageways at the top of the checkerwork as at 19. These passageways extend throughout the checkerwork construction including the lowermost courses embodying the invention. A cold air inlet 20 is provided near the base of the structure leading into passages 21 and passage 18 has an opening 22 leading to the heater, and an opening 23 leading to the blast furnace 90 proper. On the top of arches 14 is a horizontal row or layer of bricks 24 and on top of these bricks 24 is laid the first course or first layer of bricks comprising the checkerwork and designated generally by the letter "A", and is the course shown in Figure 3.

This course comprises bricks A1 laid on edge end to end across bricks 24, and between them are placed bricks A2, which also rest on bricks 24. Bricks A1 are the standard rec-

tangular bricks and are preferably 15 x 9 x 3 inches. With the exception of special bricks A2, all of the bricks comprising the main checkerwork are of equal thickness and preferably that thickness is three inches. Also with the exception of special bricks A2 and the special bricks C3 and C4 the bricks are all of the standard rectangular construction and preferably 15 x 6 x 3 or 12 x 6 x 3.

10 The second course consists of standard rectangular bricks B1, B2, and B3, bricks B1 resting on bricks A1, but in staggered relation thereto and on alternate rows. Bricks B2 extend across bricks A1 and A2 and between and abutting bricks B1. These special bricks A2 are also somewhat taller than the width of bricks A1, and have a central recess 25 in the top thereof, the bottom of which recess is approximately on a level with the top of bricks A1 for forming a chair to support a transversely arranged brick at the joint. This provides a continuous bearing surface for bricks B2 which extend across bricks A2 and A1. Along bricks A1 on the remaining alternate rows and between bricks 25 B2 are bricks B3. The third course consists of bricks C1, C2, C3, and C4, of which bricks C1 and C2 are standard rectangular bricks, and bricks C3 and C4 are the special bricks shown in Figure 9. Bricks C3 and C4 are similar to the standard rectangular bricks, but have a central recess 26, the width of which is equal to the thickness of the bricks and the recess is cut one-half way through. 35 Bricks C3 and C4 are identical except that one is the reverse of the other, that is to say, the two are fitted together to form a dovetailing cross. Special bricks C3 are laid along bricks B1 and centrally therewith and special bricks C4 are placed across bricks C3 so that the ends of bricks C4 rest on the adjacent ends of bricks B2. Bricks C2 extend across and rest on bricks B3 of the second course and are supported at the centre by 45 the adjoining ends of bricks B1. Bricks C1 extend along bricks B3 and overlap the adjacent ends of the latter, and bricks C1 and C2 form a rectangle around bricks C3 and C4. The fourth course comprising bricks D1 and D2 is the standard checker course, and is the arrangement with which the major portion of the remainder of the stove is constructed. It will be seen that throughout the several courses ample spaces for the circulation 55 of heated air or gases is provided. The stove is operated in the usual manner, the bricks comprising the checkerwork being heated by the introduction of heated air or gases through opening 22, after which cold air introduced into the stove through opening 20 will be heated by the hot bricks and may then be let into the furnace through opening 23.

60 65 Having thus described my invention, what

I claim as new and desire to secure by United States Letters Patent, is:

1. A brick construction for use in blast furnace stoves and the like comprising a course of standard bricks arranged in parallel rows with the contiguous bricks in each of said rows abutting in end to end formation, and a plurality of spacing bricks interposed between said parallel rows and overlapping the joints between the bricks in said rows, said spacing bricks being formed with dimensions to provide ample spaces therebetween to form passageways between said parallel rows and to provide supplemental supports at the said joints for a second course of spaced parallel standard bricks arranged transversely of said first mentioned parallel rows. 70 75 80

2. A brick construction for use in blast furnace stoves and the like comprising a course of standard bricks arranged in parallel rows with the contiguous bricks in each of said rows abutting in end to end formation, a plurality of spacing bricks interposed between said parallel rows and overlapping the joints between the bricks in said rows, said spacing bricks being formed with dimensions to provide ample spaces therebetween to form passageways between said parallel rows and to provide joint reinforcements for the bricks of said parallel rows, and a second course 85 90 95 comprising spaced parallel standard bricks arranged transversely of said first mentioned parallel rows and resting upon said reinforced joints. 100

3. A brick construction for use in blast furnace stoves and the like comprising a course of standard bricks arranged in parallel rows with the contiguous bricks in each of said rows abutting in end to end formation, a plurality of spacing bricks interposed between said parallel rows and overlapping the joints between the bricks in said rows, said spacing bricks being formed with dimensions to provide ample spaces therebetween to form passageways between said parallel rows and to provide joint reinforcements for the bricks of said parallel rows, and a second course comprising spaced parallel standard bricks arranged transversely over the parallel rows of the first course and resting upon said reinforced joints and parallel rows of abutting standard bricks resting upon alternate rows of the first course and breaking joints therewith. 105 110 115

4. A brick construction for use in blast furnace stoves and the like, comprising a course of standard bricks arranged in parallel rows with the contiguous bricks in each of said rows abutting in end to end formation, and a plurality of spacing bricks interposed between said parallel rows and overlapping the joints between the bricks in said rows, said spacing bricks being formed with one dimension greater than the width of the standard bricks of the first said parallel rows 120 125 130

and being recessed to form a chair for receiving a transverse brick in a superimposed course.

5. A brick construction for use in blast furnace stoves and the like, comprising a course of standard bricks arranged in parallel rows with the contiguous bricks in each of said rows abutting in end to end formation, a plurality of spacing bricks interposed between said parallel rows and overlapping the joints between the bricks in said rows, said spacing bricks being formed with one dimension greater than the width of the standard bricks of the first said parallel rows 10 and being recessed to form a chair for receiving a transverse brick in a superimposed course, and a second course of standard bricks, comprising spaced bricks arranged transversely of said parallel rows and supported over said joints in said chairs, parallel rows in abutting end to end relation resting upon the alternate parallel rows of the first course.

6. A brick construction for use in blast furnace stoves and the like, comprising a course of standard bricks arranged in parallel rows with the contiguous bricks in each of said rows abutting in end to end formation, a plurality of spacing bricks interposed between said parallel rows and overlapping the joints between the bricks in said rows, said spacing bricks being formed with one dimension greater than the width of the standard bricks of the first said parallel rows and being recessed to form a chair for receiving a transverse brick in a superimposed course, and a second course of standard bricks, comprising spaced bricks arranged transversely of said parallel rows and supported over said joints in said chairs, parallel rows in abutting end to end relation resting upon the alternate parallel rows of the first course, and bricks over and supported by the remaining alternate rows of the first said course with their ends abutting said transversely arranged parallel bricks.

7. A brick construction for use in blast furnace stoves and the like, comprising a course of standard bricks arranged in parallel rows with the contiguous bricks in each of said rows abutting in end to end formation, a plurality of spacing bricks interposed between said parallel rows and overlapping the joints between the bricks in said rows, said spacing bricks being formed with one dimension greater than the width of the standard bricks of the first said parallel rows and being recessed to form a chair for receiving a transverse brick in a superimposed course, and a second course of standard bricks, comprising spaced bricks arranged transversely of said parallel rows and supported over said joints in said chairs, parallel rows in abutting end to end relation resting upon the alternate parallel rows of the first course, bricks over and

supported by the remaining alternate rows of the first said course with their ends abutting said transversely arranged parallel bricks, and a third course of bricks comprising a plurality of pairs of slotted interlocking bricks arranged in the form of a Greek cross with the intersecting portions resting upon intermediate portions of abutting bricks of said parallel brick rows of said second course. 75

8. A brick construction for use in blast furnace stoves and the like, comprising a course of standard bricks arranged in parallel rows with the contiguous bricks in each of said rows abutting in end to end formation, a plurality of spacing bricks interposed between said parallel rows and overlapping the joints between the bricks in said rows, said spacing bricks being formed with one dimension greater than the width of the standard bricks of the first said parallel rows and being recessed to form a chair for receiving a transverse brick in a superimposed course, and a second course of standard bricks, comprising spaced bricks arranged transversely of said parallel rows and supported over said joints in said chairs, parallel rows in abutting end to end relation resting upon the alternate parallel rows of the first course, bricks over and supported by the remaining alternate rows of the first said course with their ends abutting said transversely arranged parallel bricks, and a third course of bricks comprising a plurality of pairs of slotted interlocking bricks arranged in the form of a Greek cross with the intersecting portions resting upon intermediate portions of abutting bricks of said parallel brick rows of said second course. 80

9. A checkerwork for blast furnace stoves having spaced arches comprising in combination a first course consisting of spaced rows of standard bricks across said arches, and special bricks on said arches between said spaced rows of standard bricks, a second course comprising rows of standard bricks on alternate rows of the standard bricks of the first course, standard bricks between said rows of the second course and across the remaining alternate rows of the first course and on the said special bricks, and standard bricks on said remaining alternate rows and between said second mentioned bricks of the second course. 95

10. A checker brick construction for use in blast furnace stoves and the like, comprising, in combination, a course of standard bricks disposed immediately above the arches in the stove, a course of standard bricks arranged to occupy the upper part of the stove, and an intermediate course of specially formed bricks interposed between the upper and lower courses of standard bricks. 100 110 115 120 125 130

11. A checker brick construction for use in blast furnace stoves and the like, comprising, in combination, a course of standard bricks disposed immediately above the arches in the stove, a course of standard bricks arranged to occupy the upper part of the stove, and a plurality of intermediate courses of specially formed bricks interposed between the upper and lower courses of standard bricks.
- 10 Signed at Chicago, Ill., this 17th day of September, 1929.
